UNITED STATES PATENT OFFICE.

CHRISTOPHER C. CUNNINGHAM, OF MONTREAL, QUEBEC, CANADA.

SHOE SHANK.

Application filed October 23, 1924. Serial No. 745,454.

This invention relates to new and useful improvements in shoe shank stiffeners and the object of the invention is to provide a shank stiffener which will be simple and robust in construction and which will also serve as a means for preserving the shape and form an arch support.

Another object is to provide a shoe shank which will be easily attached to the shoe and which will have means provided at one end to accommodate the heel attaching means.

In my invention I provide a metal strip having a grooved portion extending from one end to within a short distance of the other end, which is flattened out and provided with notches on each side so that a staple may be inserted in the notches for attaching the shank to the underside of the sole of the shoe. The grooved end of the strip is provided with tapering sides adapted to pass between the means for securing the heel to the upper of the shoe. The last mentioned end may be provided with an aperture therein, through which a brad may be placed to hold the stiffener in position. The strip is bent or curved in the longitudinal direction to conform to the arch of the foot or the instep or shank of the shoe. One end of the strip passes under the hollow of the heel and the flattened end is so bent that it underlies the ball of the foot of the wearer.

In the drawings:

Figure 1 is a sectional elevation of a shoe with my improved shoe shank stiffener attached thereto.

Figure 2 is a plan view of my improved shank stiffener.

Figure 3 is a side elevation of my improved shank stiffener.

Figure 4 is a sectional elevation of the shank taken on the line 4—4 Figure 3.

Figure 5 is a sectional elevation of the shank taken on the line 5—5 Figure 3.

Figure 6 shows a perspective view of one modified form of stiffener.

Referring more particularly to the drawings, 11 designates the upper of a shoe having an inner sole 12, an outer sole 13 and a heel 14. In the instep or shank 15 between the heel and the ball 16 of the foot, a stiffener 17 is securely attached to the insole by a staple 18 at one end and a brad 19 at the other end. The stiffener 17 is formed of a

strip of steel or such like material bent in 55 the longitudinal direction to conform to the arch or instep of the foot. The strip of steel has also a groove 20 formed therein by bending the strip in the lateral direction in the form of an obtuse U with the upper ends 21 60 of the U partially flattened out to form a bearing surface for the stiffener against the instep. The groove extends in the longitudinal direction from one end 22 of the strip to within a short distance of the other 65 end 23, the greatest depth of groove being at a point 24 positioned midway between said ends. The end 22 or grooved end of the strip is narrowed down or beveled at the edges 25 to clear the attaching nails of 70 the heel, said nails being positioned one on each side of the strip in a shoe with standard wooden heel construction. The end 22 is placed in the hollow of the heel and the end 23 is flattened out and adapted to be 75 placed under the ball of the foot between the insole and the outsole. Notches 26 are formed in the sides of the strip at the end 23 so that the sides of the prongs 27 of the staple will engage with the sides of the 80 notches to hold the stiffener against lateral movement. In the drawing I have shown a brad 19 passing through an aperture 28 formed in the end 22, but this attaching means may be modified and a staple used, 85 the prongs of the staple (not shown) being adapted to engage with the bevelled edges of this end. I have also shown triangular shaped notches 26 in the end 23 but the shape of these notches may be modified to 90 suit requirements. Other such modifications may be made without departing from the spirit of the invention.

The operation of the device is as follows: The insole is cut and formed to the 95 desired shape and the shank support is placed on the underside of the insole with the concave side of the groove facing towards the said insole. The flattened end of the stiffener is placed under the ball of 100 the foot and is attached to the insole by a staple or such like means engaging with the notches. The grooved end is placed under the heel and is attached to the insole by means of the brad. The stiffeners are 105 grooved and bent to the shape of the arch before attaching them to the insoles and are very easily aligned by placing the edges of

the notches in line with the break in the sole. The tapered end under the heel clears the heel attaching nails. The outer sole is sewn or otherwise attached to the insole at the edges and may be pressed to accommodate the projecting stiffener. The grooved stiffener forms a very strong arch support which will not buckle under severe walking strains.

- 10 In the modification shown in Figure 6, upwardly projecting prongs 30 are provided and made integral with the strip. The prongs are pressed into the insole and their ends riveted over to hold the stiffener in position against the insole. The prongs may be pressed out of the side or ends of the strip leaving the notches 26 as shown. The prongs may also be twisted to strengthen them against buckling when they are driven into the insole. The twisted formation also provides a splendid gripping means between the stiffener and the insole. When the shank is made according to Figure 6, it will be readily understood that no other attaching means than the prongs is required.

Having thus described my invention, what I claim is:—

A shank stiffener for shoes and the like comprising a narrow strip of metal grooved in the longitudinal direction, the groove being in the form of an obtuse U extending from one end to within a short distance of the other end of the shank, the deepest part of the groove being situated at approximately the center of the strip, the ungrooved portion of the strip being substantially flat and the grooved end of said strip being formed with tapered side edges, there being slots punched in the edges of the strip at the flattened end thereof and said strip being bent to conform to the shape of the instep or arch of the shoe and being provided with means for attaching same to the underside of the insole with the flat end under the break of the sole and the other end in the hollow of the heel with the concave side of the strip facing said insole.

In witness whereof, I have hereunto set my hand.

CHRISTOPHER C. CUNNINGHAM.
